OF NEW JERSEY

METHOD OF FORMING CAN CLOSURES

Application filed April 4, 1930. Serial No. 441,445.

This invention relates to a novel and improved method of forming a metal closure for cans, and will be best understood from the following description and the annexed drawing, in which we have shown a selected way of practicing the invention and in which:—

Fig. 1 is a view partly in elevation and partly in section showing the top of a can 10 having applied thereto a closure made according to our novel method.

Fig. 2 is a section on the same plane as the sectional part of Fig. 1, showing a portion of the closure on an enlarged scale, before attachment to the can.

Figs. 3, 4, 5, 6, 7, 8 and 9 are views showing successive steps performed on a blank to transform it into the closure.

Referring first to Fig. 1, we have shown 20 the invention as used in connection with a can 1 having a top designated generally at 2, and which is secured to the can at 3 by any suitable means such as a double seam. This top forms a closure for the can and is preferably provided with a central recess 4 adapted to receive the plug 5.

In the bottom of the recess is disposed a 30 frangible sealing member 6 which may be made of any suitable material which can be easily cut with a knife, preferably without leaving a ragged edge. This material may be paper, cardboard, cellophane, thin aluminum, or the like, it being understood that the top is of sheet metal or relatively non-frangible material.

Referring now to Figs. 3 to 9 inclusive, in 40 Fig. 3 is shown a blank with which the method of forming the closure may start, this blank being in the form of a cup-shaped member having a flat bottom 7 surrounded by a cylindrical wall 8, this bottom and wall defining a recess. By the next operation, the bottom is depressed, as shown in Fig. 4, and the cylindrical wall 8 is made of smaller diameter, 45 a flange 9 being formed at the same time.

By the next step, the flange is formed with a gutter 10, as shown in Fig. 5, and by the following step the bottom 7 is brought to the position shown in Fig. 6, the wall 8 being 50 folded back on itself to form an edge 11 in

the shape of a fold, it being noted that this edge is displaced from the bottom in a direction lengthwise of the wall 8.

The bottom 7 is then provided with an opening with its edge 12 folded downwardly, 55 as seen in Fig. 7, and by the next step this edge is folded toward the wall to form the bead 13. The sealing member 14 is then placed against the bead and the folded edge 11 is bent inwardly at the same time that the bead 13 is bent downwardly and outwardly toward the folded edge 11.

It will be seen that the bead 13, as well as the folded edge 11, extend transversely to the plane of the sealing member, and that the sealing member is received within the space between these two elements, being bent twice in reverse directions, first around the bead 13 and then around the folded edge 11. 60 By this arrangement the sealing member is clamped between two smooth elements overlapping one another, and while these elements lock the bent edge portion of the sealing member between them, nevertheless there is no ragged cut edge of metal to contact with the sealing member. Moreover, the construction 65 is one which may be easily made by suitable dies, without the dies at any time coming in contact with the sealing member which is protected at all times from the dies. At the same time, when the frangible sealing member is cut for removal, the bead being disposed transversely to the plane of the sealing member, and also being smooth at its exposed portion, it does not present any exposed 70 rough edge which might cause damage to the hands of a person opening the can.

The joint between the sealing member and the top may be made still tighter by placing a suitable sealing compound in the space between the bead and the folded edge, or by using a sealing member which is coated with paraffin, or the like, which will be heated during the sealing step and thus flow into the spaces between these two elements. In any case, automatic sealing machinery may be 75 used in practicing the invention.

While we have shown the invention as applied to the top, it is to be understood that, 80 if desired, it may be applied also to the plug, 100

in which case of course the contents will be permanently exposed or some other temporary closure provided therefor.

We claim:—

1. The method of manufacturing a can top which comprises drawing the top with a flat bottom connected to a peripheral wall, forcing said bottom upwardly by redrawing to form a close fold where the bottom is joined to the wall, cutting an opening in the bottom while leaving an inwardly extending annular portion adjacent the periphery thereof, placing a frangible sealing member on said annular peripheral portion, and bending said fold into engagement with the edge portion of the sealing member to clamp it against said remaining annular peripheral portion of the bottom.

2. The method of manufacturing a can top which comprises drawing the top with a flat bottom connected to a peripheral wall, forcing said bottom upwardly by redrawing to form a close fold where the bottom is joined to the wall, forming a recess in the bottom adjacent the wall, cutting an opening in the bottom while leaving an inwardly extending annular portion adjacent the periphery thereof, placing a frangible sealing member on said annular peripheral portion, bending said fold into engagement with the edge portion of the sealing member to clamp it against said remaining annular peripheral portion of the bottom, and to force it into said recess.

3. The method of manufacturing a can top which comprises drawing the top with a flat bottom connected to a peripheral wall, forcing said bottom upwardly by redrawing to form a close fold where the bottom is joined to the wall, forming a recess in the bottom adjacent the wall, cutting an opening in the bottom while leaving an inwardly extending annular portion adjacent the periphery thereof, placing a frangible sealing member on said annular peripheral portion, bending said fold into engagement with the edge portion of the sealing member to clamp it against said remaining annular peripheral portion of the bottom and to force it into said recess, and filling said recess with a sealing compound.

4. The method of manufacturing a can top which comprises forming the top with a flat bottom connected to a peripheral wall, forcing said bottom upwardly to form a fold where the bottom is joined to the wall, cutting an opening in the bottom and leaving an inwardly extending portion adjacent the edge thereof, folding back said edge portion to form a bead on the side next said fold, and bending said fold into engagement with the edge portion of the sealing member to clamp it between the fold and the bead.

5. The method of manufacturing a can top which comprises forming the top with a flat bottom connected to a peripheral wall,

forcing said bottom upwardly to form a fold where the bottom is joined to the wall, cutting an opening in the bottom and leaving an inwardly extending portion adjacent the edge thereof, folding back said edge portion to 70 form a bead on the side next said fold and spaced from said wall, and bending said fold into engagement with the sealing member between said bead and wall to force it into the space between the bead and wall. 75
